UNITED STATES PATENT OFFICE.

STACY B. HASELTINE, OF CHICAGO, ILLINOIS, ASSIGNOR TO WILLIAM H. MINER, OF CHAZY, NEW YORK.

DRAFT-GEAR YOKE.

1,242,800.

Specification of Letters Patent.

Patented Oct. 9, 1917.

Application filed April 13, 1916, Serial No. 90,837. Renewed August 27, 1917. Serial No. 168,456.

To all whom it may concern:

Be it known that I, STACY B. HASELTINE, a citizen of the United States, residing at Chicago, in the county of Cook and State 5 of Illinois, have invented a certain new and useful Improvement in Draft-Gear Yokes, of which the following is a full, clear, concise, and exact description, reference being had to the accompanying drawings, forming 10 a part of this specification.

This invention relates to improvements in draft gear yokes.

For several years past, the railroads have been desirous of obtaining a draw-bar and 15 yoke connection which will avoid slotting of the sills and at the same time be readily detachable. Furthermore, the railroads are demanding a yoke connection of the above character which is adapted to all types of 20 standard draw-bars whether the latter have coupler key slots or not. A further requisite demanded by the railroads is a detachable draw-bar and yoke connection so arranged that all the parts are easily accessible 25 and wherein the draw-bar may be removed or replaced without disturbing the gear proper.

The object of my invention is to provide a yoke for railway draft riggings of simple 30 construction and which will embody all the advantageous features above indicated.

In the drawing forming a part of this specification, Figure 1 is a side elevation of one form of yoke embodying my improvements. Fig. 2 is a horizontal section of the yoke illustrated in Fig. 1 and taken on the line 2—2 thereof. Fig. 3 is a front end elevation of the yoke. Figs. 4 and 5 are detail perspectives of one of the locking 35 blocks and spreader employed. And Fig. 6 is a longitudinal, central section of a tandem yoke embodying my improvements.

Referring to said drawing, 10 denotes a standard draw-bar having the usual butt 11 45 provided with upper shoulder 12 and lower shoulder 13. The yoke A, which as shown is preferably a steel casting, is provided with upper arm 14, lower arm 15, rear connecting piece 16, and a hollow, boxlike hood 50 or head 17 at its front end, the hood being open at the front and provided with side walls 18—18, and upper wall 19, the upper wall 19 being provided on its inner face with an integral, transversely extending gib 55 or shoulder 20, the latter being adapted to

cooperate with the upper shoulder 12 of the draw-bar. Within the yoke a shock absorbing member is illustrated conventionally by dotted lines, the shock absorber shown in the drawing being a well known 60 type of friction gear.

The lower wall 21 of the hood is offset downwardly from the lower arm 15 of the yoke so that when the locking blocks, hereinafter described, are removed, the draw-bar may be dropped down to clear the shoulder 20 and thereby removed. To lock the draw-bar in position, I have provided two locking blocks 22 and 23 and a spreader 24. The locking-blocks 22 and 23 are made right 70 and left as will be understood, and each comprises a horizontally extending portion 25, upwardly extending shoulder or gib 26 which engages the lower shoulder 13 of the draw-bar, the shoulder 26 being extended 75 laterally outwardly from the horizontal portion 25 as indicated at 27. Each portion 27 of each block is adapted to be inserted laterally or sidewise through corresponding rectangular openings 28 in the side walls 80 of the hood, the latter being suitably reinforced around said openings as indicated at 29. The spreader member 24 comprises a horizontal flat portion 30 which tapers 85 slightly toward its rear end and is pointed as indicated at 31, an upstanding shoulder or gib 32 and a depending perforated ear 33. The ear 33 is adapted to aline with a correspondingly formed ear 34 on the underside of the hood and the block 30 is detachably held in position by a bolt 35.

The parts are assembled by first placing the draw-bar within the hood, then lifting the draw-bar and inserting the blocks 22 and 23 thereunder from the front end of the 95 yoke. The width of the blocks 22 and 23 is such that both may be inserted simultaneously when the spreader member 24 is not in place. The blocks 22 and 23 are then pushed rearwardly until the shouldered portions thereof come into alinement with said openings 28—28. Thereupon, the blocks 22 and 23 are pushed outwardly or separated which may be done with any suitable tool or by inserting the tapered spreader 24. As the latter is pushed inwardly it is apparent that it will force the locking blocks 22 and 23 to their outermost position and so long as the spreader member 24 remains in place, the blocks 22 and 23 will be held in oper- 100 105 110

ative position. It will be understood that the inner faces 36—36 of the horizontal portions of the locking blocks are beveled to correspond with the taper of the spreader block 24.

In the construction illustrated in Fig. 6, all of the parts are the same except that the yoke A' is provided with upper and lower shoulders 40—40 which are arranged to be engaged by the rear face of the draw-bar butt so that the yoke will be pushed rearwardly in buffing and thereby adapt the invention to tandem yokes.

Although I have herein shown and described what I now consider the preferred means of carrying out my invention, the same is merely illustrative and I contemplate all changes and modifications that come within the scope of the claims appended hereto.

I claim:

1. A yoke provided with a hooded forward end within which is adapted to be received a shouldered draw-bar butt, the side walls of the hooded end being provided with shoulders, said yoke being provided with means arranged to engage the upper shoulder of a draw-bar butt, and devices, coöperable with the lower shoulder of a draw-bar butt, for detachably locking the yoke to a draw-bar, said devices including shouldered blocks insertible and removable from the front end of the yoke while the draw-bar is in place, said blocks being movable laterally after the same have been inserted within the hood to thereby engage with said shoulders on the side walls of the hooded end, and means for retaining said blocks in operative position.
2. A yoke provided with a hooded forward end within which is adapted to be received a shouldered draw-bar butt, said yoke being provided with means arranged to engage the upper shoulder of a draw-bar butt, and devices, coöperable with the lower shoulder of a draw-bar butt, for detachably locking the yoke to a draw-bar, said devices

including two blocks and a spreader, all insertible from the front end of the yoke.

3. A yoke provided with a hooded forward end within which is adapted to be received a shouldered draw-bar butt, the side walls of the hooded end having recesses, said yoke being provided with means arranged to engage the upper shoulder of a draw-bar butt, and devices, coöperable with the lower shoulder of a draw-bar butt, for detachably locking the yoke to a draw-bar, said devices including a plurality of shouldered blocks insertible from the front end of the yoke, some of said blocks being shiftable laterally to engage in said recesses.

4. A keyless yoke of the character described having a hooded forward end the latter having an integral transversely extending upper shoulder arranged to engage the upper shoulder of a draw-bar, a pair of shouldered blocks insertible from the front end of the yoke and arranged to be positioned beneath the draw-bar with the shoulders engaging the lower shoulder of a draw-bar butt, and means for holding said shouldered blocks in operative position.

5. In a device of the character described, the combination with a shouldered draw-bar, of a cast steel yoke, said yoke having a hooded forward end within which is received the butt end of the draw-bar, and means for detachably locking said draw-bar and yoke together, said means including a pair of shouldered blocks insertible from the front end of the yoke, said blocks having laterally extended shoulders, the side walls of the hooded end having recesses into which said laterally extended shoulders are adapted to be positioned, and a spreader member also insertible from the front end of the yoke between said blocks, and detachable means for holding said spreader in position.

In witness that I claim the foregoing I have hereunto subscribed my name this 15th day of March, 1916.

STACY B. HASELTINE.
